WELTING INSTRUMENTALITY FOR KNITTING MACHINES AND METHOD OF USE

Eugene M. Zesch, Shillington, Pa., assignor to
 Karl Lieberknecht, Inc., Reading, Pa., a corporation of Pennsylvania

Application January 14, 1949, Serial No. 70,914

8 Claims. (Cl. 66—96)

1

This invention relates to instrumentalities useful in connection with straight knitting machines of the "Cotton" type ordinarily employed in the commercial production of fashioned hosiery and the like, in closed welt forming operations. It is also concerned with an improved method of loop manipulation incident to operations of the kind referred to.

In the automatic performance of welt turning operations on straight stocking knitting machines, alternate loops of a starting course on the needles of the machine are engaged by hooked instrumentalities anchored in a bar, which, during the formation of a definite length of welt fabric, is moved outward of the machine to draw off the web as it is being knitted, and which is later moved reversely to fold over the fabric and to bring its hooked instrumentalities into registry with the needles for restoration to them of the loops of the aforesaid starting course, whereupon the knitting is resumed for completion of the stocking blanks. With weling instrumentalities as heretofore constructed, it was necessary to pass the hooks thereof bodily through the alternate loops of the initial or starting courses, for example as shown in Fig. 22 of U. S. Patent #2,269,463 granted to Karl R. Lieberknecht on January 13, 1942. These loops were thus unduly enlarged with resultant formation, upon subsequent closing of the welts, of sleezy seam junc- tures which detracted from the otherwise pleasing appearance of the stockings.

My invention is directed in the main toward overcoming the above drawback, which I have made possible of realization in practice, as hereinafter more fully disclosed, through provision of improved weling instrumentalities characterized by having rearwardly offset elongate hooks with the hook fronts substantially in aligned relation to said shanks; and through the further provision of a novel method of actuating said instrumentalities in such a way as to avoid the necessity for passing their hooks bodily through the loops of the starting courses at the initiation of the knitting.

Other objects and attendant advantages will appear from the following detailed description of the attached drawings, wherein Fig. 1 is a view drawn to an enlarged scale showing the elevation of one side of an improved weling instru- mentality conveniently embodying my invention.

Fig. 2 shows the elevation of the opposite side of the instrumentality.

Fig. 3 shows the rear elevation of the instru- mentality.

2

Figs. 4—6 are detail sectional views taken as indicated respectively by the angled arrows IV—IV, V—V, and VI—VI in Fig. 1.

Figs. 7—17 are fragmentary views in cross section of a straight knitting machine showing successive steps in the starting and closing of welt fabric with the aid of my improved loop transferring instrumentalities.

Figs. 18—22 are fragmentary detail views looking as indicated respectively by the arrows XVIII—XVIII, XIX—XIX, XX—XX, XXI—XXI and XXII—XXII in Figs. 7, 8, 9, 11 and 12.

With reference first more particularly to Figs. 1—3 of these illustrations, it will be noted that as there shown, my improved loop transferring instrumentality generally designated by the numeral 25, has a shank with upper and lower portions or segments 26, 27 disposed in relatively wide obtuse angular relation. The upper portion 26 is round in cross section as will be seen in Fig. 4, and its distal end is bent laterally as at 28 for anchorage purposes in a supporting bar. The lower shank portion 27, on the other hand, has flat sides 29, see Fig. 5, is beveled at the rear as at 30, and is provided centrally of its front with a round-bottomed longitudinal V groove 31 capable of receiving the spring beard of a knitting needle as later on explained. Formed as an integral continuation of the lower shank portion 27, is a rearwardly offset straight vertically-elongate hook 32 with a narrow lateral yarn entrant throat 33 at the front between the region of emergence of the hook back 34 with said lower shank portion and the tip of the hook front 35, said throat being inclined inwardly and downwardly toward the hook interior. The hook back 34 is beveled as at 36 in continuation of the bevel 30 of the lower shank portion 27, and its inner surface is rounded as at 37 as best seen in Fig. 6. The hook front 35 is substantially in line with the shank portion 27, being very slightly inclined toward the hook bight 38. The hook front 35 is moreover rounded at the inside as at 39 in Figs. 2 and 6 and, like the shank portion, provided centrally of its outer face with a longitudinal needle beard receiving V groove 40 which has a square bottom as best seen in Fig. 6. The bottom or bight end of the hook 34 is beveled to a relatively sharp edge as indicated at 41.

The straight knitting machine partly shown in Figs. 7—17 to illustrate how the instrumentalities 25 are utilized in weling operations, has the usual series of spring beard needles N, sliding sinkers and dividers S and D and knockovers K, the beards of the latter being closed in normal stitch

formation, as ordinarily, by contact with a fixed presser edge E on the stationary sinker head H. The mechanism for actuating the needles, sinkers, dividers, and knockovers may be of any suitable well known construction and, for this reason, has been omitted from the drawings. As shown, the instrumentalities 25 are anchored in the supporting bar 42, and it is to be understood that they are spaced for capacity to cooperate with alternate needles N' of the series N.

Operation

In Fig. 7, the yarn y has just been laid for the starting course of the knitting and kinked as in Fig. 18 by the sinkers S around the shanks of neighboring pairs of needles while the needles are in fully raised position. The bar 42 is being moved downward as indicated by the arrow, to carry the instrumentalities 25 toward the fronts of the needles as the dividers D start outward for final division of the yarn between the needles as in Fig. 19.

Fig. 8 shows the instrumentalities 25 moving down with the backs of their hooks 32 bearing against the presser edge E, and with their throats 33 at the yarn feeding level, the needles having moved inward so that the beards of the alternate ones N' are engaged in the grooves in the lower shank portions 27 and thereby held closed. It is to be understood that the free intermediate needles are not moved into contact with the presser edge for closure of their beards at this stage, and hence retain their loops. As the needles continue downward from the position of Fig. 8 to the knockover level as in Figs. 9 and 20, the loops l previously held by the alternate needles N' are engaged within the hooks 32 of the instrumentalities 25 as the sinkers and dividers recede. Bar 42 is thereafter moved outward as in Fig. 10 to carry the instrumentalities 25 over the tops of the needles N' while the latter are still depressed, whereby the loops l are slid off the noses of the sinkers and dividers and drawn into the bottoms of the hooks 32. Thus, in accordance with my invention, the entire hook portions of the instrumentalities 25 are not passed through the loops l of the starting course as was necessary in the patent hereinbefore referred to, with consequent avoidance of the dilation of these loops and ultimate formation of a sleezy and unsightly welt closures.

In Fig. 11 the sinkers and dividers have been projected over all of the fabric loops to restrain them as the needles are elevated to receive new yarn y'. The plan of the loop formation in the first course being at this stage as shown in Fig. 21.

In Fig. 12, the second course has been formed from the newly laid yarn in the normal manner and the loops l' thereof drawn by the needles through the loops l of the first course, the plan of loop formation being then as shown in Fig. 22. The knitting thereupon proceeds for a time until the desired length of welt fabric F has been produced as in Fig. 13. During this phase of the knitting the welt fabric is continually drawn off by gradual outward movement of the welt bar 42 in the usual manner.

After placement of a welt rod R as in Fig. 13, the bar 42 is moved inward of the machine as the needles descend, and eventually downward as in Fig. 15 to bring the instrumentalities between the alternate needles N' and the presser edge E. During the topping-on stage which is illustrated in Fig. 15, alternate needles N' move up through the loops l of the starting course still

retained by the instrumentalities 25, while the last formed loops l' are retained by said needles whereof the beards are held closed by contact with the hook fronts of said instrumentalities.

As the bar 42 continues downward to bring the throats of the instrumentalities to the knock-over level, the sinkers and dividers are advanced over the now doubled over welt fabric F as in Fig. 16. During the dwell of the bar 42 in its lowermost position as the needles continue to rise and concurrently recede outward, the loops l are drawn laterally out of the throats of the instrumentalities for retainment by alternate needles N' as also shown in Fig. 16.

Finally, the bar 42 is elevated for withdrawal of its instrumentalities 25 from the field of knitting as in Fig. 17 until their use is again required. With the welt now finished and closed, the machine continues in its operation until the stocking is completed as ordinarily.

Due to the grooving of the shanks of the instrumentalities 25 as well as of their hook fronts, it will be seen that a more positive hooking of the alternate fabric loops N' is assured as the latter are pressed off said needles. This permits the use of a shorter starting course for the ultimate formation of a firmer seam when said course is transferred back to the needles. It is moreover advantageous in that it precludes the possibility of damage to the needle beards during the hooking up operation.

Having thus described my invention, I claim:

1. A welting instrumentality for use with needles of a knitting machine in the manner described, having a shank; a rearwardly-offset elongate hook at one end of the shank with its back parallel to the adjacent portion of the shank; and a relatively narrow yarn entrant throat between the tip of the hook and the region of emergence of the shank with the hook back.

2. A welting instrumentality according to claim 1, wherein the hook front is substantially in line with the shank; and wherein the throat is inclined inwardly and downwardly toward the interior of the hook.

3. A welting instrumentality according to claim 1, wherein the shank and the hook back are beveled at the rear; and wherein the hook front, back and bottom are rounded on the inside.

4. A welting instrumentality for use with spring beard needles of a knitting machine in the manner described having a shank with a longitudinal needle beard receiving groove at the front; a rearwardly-offset elongate hook at one end of the shank; a relatively narrow entrant throat for yarn between the tip of the hook front and the region of emergence of the hook back with the shank, said hook front being substantially in line with the shank and likewise provided with a longitudinal needle beard receiving groove substantially in alignment with the groove in said shank.

5. A welting instrumentality according to claim 4, in which the throat is inclined inwardly and downwardly toward the interior of the hook.

6. A welting instrumentality according to claim 4, wherein the shank and the hook back are beveled at the rear, and wherein the hook front, back and bottom are rounded at the inside.

7. The method of starting fabric for a welt in a straight knitting machine having a series of spring beard needles, sinkers and knockovers, a presser edge and loop engaging instrumentalities to cooperate with alternate needles each having a shank with a rearwardly offset elongate terminal hook whereof the back is parallel to

the adjacent portion of the shank, and a narrow lateral yarn entrant throat between the tip of the hook and the region of emergence of the shank with the hook back, said method comprising the steps of kinking yarn by the sinkers about the shanks of elevated needles; moving the instrumentalities en masse to the fronts of the needles with the backs of their hooks bearing against the presser edge and with their throats at the yarn feeding level; then moving the needles inward for closure of the beards of alternate needles by engagement with the shanks of the hook instrumentalities while above the yarn feeding level, and concurrently moving the needles downward incident to retraction of the sinkers for lateral displacement of the loop kinks over the tips of the hook fronts and into the hooks of the instrumentalities; then moving the instrumentalities outward over the needles after the latter have descended to the knockover level; and then, after elevation of the needles, causing new yarn to be kinked about the needle shanks by the sinkers in preparation for the drawing of the next course of fabric loops.

8. The method of forming a closed welt after the steps recited in claim 7, by continuing outward movement of the instrumentalities for a time for the production of a sufficient length of welt fabric by normal knitting; then moving the instrumentalities inward en masse to again bring

10

15

30

the backs of their hooks into contact with the presser edge as the sinkers are advanced over the fabric and as the needles rise from the knockover level with the beards of alternate needles pressing against and closed by engagement with the hook fronts, so that the loops of the last course knitted are retained while said needles pass up through the loops of the first knitted course in the hooks to eventually remove the last mentioned loops out through the throats of the instrumentalities; and finally, as the needles are moved outwardly incident to completing their rise to take new yarn, withdrawing the now empty instrumentalities from the region of stitch formation.

EUGENE M. ZESCH.
